UNITED STATES PATENT OFFICE.

FRED A. NOETZLI, OF OAKLAND, CALIFORNIA.

DAM CONSTRUCTION.

1,410,217.

Specification of Letters Patent. Patented Mar. 21, 1922.

Application filed June 16, 1919. Serial No. 304,572.

To all whom it may concern:

Be it known that I, FRED A. NOETZLI, a citizen of Switzerland, residing at Oakland, in the county of Alameda and State of California, have invented certain new and useful improvements in Dam Construction, of which the following is a specification.

This invention relates to improvements in dams and more particularly to masonry dams of the arch type, and it has for its object to build dams safer and more economically. An arch dam may be considered either as an arch reaching from top to bottom, or as a plurality of superposed arches.

In the single or multiple arch dams which heretofore have been constructed, it has been shown that there is the tendency in the lower parts of the dam to produce open cracks either between foundation and masonry or higher up in the masonry itself and in more or less horizontal directions. Many among these curved dams also have developed vertical cracks in the upper portions due to shrinkage and temperature stresses. In no dam built thus far, to the best of my knowledge, exists an economical and harmonious cooperation between vertical cantilever and horizontal arches, the vertical cantilever in arching dams always being built too stiff,

though not strong enough, to support its share of load. The result was that the cantilever cracked and deflected until the horizontal arches were able to get into action and relieve the cantilever, thus preventing ultimate failure. The objects of my invention are, first, to provide an economical division of waterpressure between vertical cantilever and superposed horizontal arches by giving the cross section of the dam a special shape and varying the radius of the horizontal arches in a special way; second, to anchor the dam by means of steel bars to the rock foundation or to a special foundation built of masonry; third, to build single arch dams overhanging in a downstream direction; and fourth, to construct arched dams with a core of masonry stronger than concrete, and covered on one or both sides with a reinforced concrete slab.

Other objects of my invention will be hereinafter set forth and more particularly pointed out in the appended claims.

In the accompanying drawings, in which my improved dam is illustrated,

Figure 1 is a down-stream elevation of 55 the improved arch dam;

Fig. 2 is a section on line 2—2 of Fig. 1;

Fig. 3 is a section on line 3—3 of Fig. 1;

Fig. 4 shows the deflection lines of vertical and horizontal arch slices in a vertical 60 plane.

Fig. 5 is a cross section of a dam showing the method of anchorage;

Fig. 6 shows in detail one method of anchorage;

Fig. 7 shows a second method of anchorage;

Fig. 8 shows a third method of anchorage;

Fig. 9 is a horizontal section through a dam with special masonry core;

Fig. 10 is a horizontal section through a dam reinforced by concrete slabs cast against up and down-stream faces of said dam.

Similar letters and numerals refer to similar parts throughout the several views.

Referring now to Fig. 1, a curved dam A is shown which rests on an enlarged base B and abuts sideways against the hillsides either directly upon the solid rock or upon a continuation of the enlarged base B which provides a smooth and uniform bearing for the arches without abrupt changes in the arch spans.

If the horizontal arch were subject to radial water-pressure only, the thickness of 85 an arch dam would have to be uniform in every horizontal plane. Temperature and shrinkage forces produce additional stresses in every horizontal arch slice and it can be proved that these secondary stresses are 90 much greater near the arch abutments than near the crown. The thickness of the horizontal arch slices therefore has to be increased towards the abutments to obtain a structure of uniform strength. To obtain 95 this, I choose the center 1 for the circular upstream face at a point farther down-stream than the center 2 for the circular downstream face, all as shown in Fig. 2.

Referring now to Fig. 3, wherein is shown 100 a cross section of the dam on the line 3—3, the arch A is supported by the enlarged base B and well anchored to said base B by means of the reinforcing bars 3 which may extend for any length up into the arch and 105 sufficiently down into the base B to insure a safe bond. The cross section of the arch is shown of about uniform thickness in the

lower part 4 just above the base B, to provide for a flexible cantilever. Farther up near 5 the thickness of the arch is increased somewhat to provide for a very strong middle arching part.

Theory shows that an arch dam in the lower portion 4 acts mainly as a vertical cantilever. This portion 4 therefore has to be rather slender to produce enough deflection near 5 so that horizontal arch action may develop. Figure 3 shows the cantilever part 4 subdivided into a plurality of substantially parallel walls. This is for the purpose of making the cantilever more flexible. Further, the thickness of the dam about midway between its top and base is increased somewhat thus providing sufficient strength for the arches. In the really arching portion of a curved dam, i. e. from 5 to the top 20 of the dam, the lowest portion 5 of these arches has to be the strongest. Therefore there exists the necessity of having a slender cantilever in the lower portion 4 of a dam and sufficient strength in a horizontal direction where arching starts to prevail. It is often of advantage to make portion 5 stronger than any other part of the dam above the base.

If we would increase also the thickness of 30 the cantilever part 3 of such a dam, this would have the undesirable effect of making the cantilever so stiff that its deflection at or near 5 or even higher up would be too small to allow appreciable arch action to develop. Thus more load would be thrown upon the cantilever than it might be able to carry, unless it be made of full "gravity section" as this alone enables a dam to sustain full water-pressure without material help from 40 horizontal arching.

The uppermost portion 6 of a slender arch dam preferably is made overhanging in a down-stream direction. With such an arrangement the weight of the dam portion 45 6 will prevent the opening of shrinkage cracks. In most existing single arch dams vertical cracks occur due to excessive tensile temperature and shrinkage stresses. This great disadvantage is overcome successfully 50 by making an arched dam sloping entirely or partially in a down-stream direction.

Referring now to Fig. 4, wherein are shown the deflection lines of vertical cantilever and horizontal arches in a vertical section of a 55 curved dam, it may be assumed for the purpose of statical design that an arch dam consists of a series of vertical dam slices, acting as cantilevers, and a series of horizontal arch slices.

Let us consider as an example a vertical section at the center of the dam. Under the assumption that the horizontal arch slices have to carry all the load, and considering also that under the influence of a drop in 65 temperature and the shrinkage in the con-

crete the arches are shortened, the arch-crowns may come into the position given by the line *a* in Fig. 4. On the other hand, if the vertical cantilever without breaking were able to and really had to sustain without the help of the upper arches all the water-pressure which falls upon it on account of its stiffness near the bottom, where practically no arch action can develop, it would deflect elastically along the line *c*. If the vertical cantilever and the horizontal arches work together, the resulting real deflection line is about in the position of the line *d*. All deflections are plotted horizontally from a vertical axis *b*.

In designing an arched masonry dam, we have to assume that part of the water-pressure is supported by vertical cantilever action and part by horizontal arching. It can be shown that in an economically designed 85 arch dam cantilever action prevails in the lower part 4 and arching in the upper part 6 of the dam. In no single arch dam, built thus far, and to the best of my knowledge, there exists an economical division of the 90 water-pressure between vertical cantilever and horizontal arches, the latter carrying very little or no load at the time of low temperature, unless the vertical cantilever be cracked. By varying in an arch dam the 95 thickness of the dam and the radii of curvature of the axis of the horizontal arch slices in such a way that the elastic cantilever deflection line *c* intersects the arch crown deflection line *a*, more economical conditions 100 are obtained for the dimensions of such a dam. At the same time the vertical cantilever has to be anchored sufficiently to the foundation that no cracks are produced at or near the base of the dam.

It can be proved, that all of the existing arched dams either do not develop any horizontal arch action at the time of low dam temperature, or that they can do so only after the cantilever has cracked partially, 110 in general in opening cracks between foundation and masonry. Not to my knowledge has ever enough, if any, steel reinforcement been placed in these parts of excessive tension in a dam as no method was known to 115 compute those stresses.

Figs. 5, 6, 7, and 8 illustrate alternative schemes how the base of a dam *D* may be anchored to the rock foundation *R* so that the vertical cantilever is able to carry its 120 share of water-pressure without breaking away from the base. Fig. 5 shows the method of anchoring a dam of any shape. Fig. 6, shows a detail of Fig. 5. A hole 7 is drilled into the rock *R* and a metal bar 8 125 introduced into said hole which is afterwards filled with cement mortar. Fig. 7 shows the steel bar 8, set into the hole 7 and protected by a tube 9 of noncorrosive material, such as galvanized iron pipe, tar paper 130

pipe, or the like, located in such places, where open cracks between rock and masonry are most liable to occur. All free spaces between metal bar 8, tube 9 and rock 5 R are thoroughly filled with cement grout. Fig. 8 shows another detail of Fig. 5. A trench 10 is excavated near the up-stream or down-stream face of the dam, this trench being filled with masonry, into which metal 10 bars 8 are anchored by bending them around other metal bars 8^a which lie in the longitudinal direction of the trench.

Referring now to Fig. 9, wherein is shown a partial horizontal section of an arch dam, the fact that the temperature stresses in an 15 arched structure increase with the third power of the thickness of the arch, makes it very desirable to build arched dams as thin as possible. It is therefore often of advantage to use a better quality of arch material 20 than common concrete, to give a structure sufficient strength in direct axial compression. Well coursed masonry of granite, etc., is very suitable for this purpose and the 25 material in general is readily available near every dam site. Nevertheless, in first class masonry arches, tension is liable to occur at certain places, due to temperature deformations. Masonry other than concrete can not 30 very well be reinforced by steel bars to take care of tensile stresses. I prefer to carry out this feature of my invention by casting concrete slabs 11 against the laid masonry 12, and embedding safely into said concrete slab 35 any number of steel bars 13 and in any direction that may be found desirable. To provide a good bond between said concrete slab 11 and the masonry core 12, I introduce additional steel bars 14 in more or less radial 40 direction passing through or part through the masonry core 12 and well anchored into the concrete slabs 11, or fastened to the bars 13. Before casting the concrete slabs 11 45 against the masonry core 12, I cover the exterior of said masonry core 12 with a thin watertight layer 15 of mortar, applied with a cement gun.

Referring now to Fig. 10, wherein is shown a partial horizontal section of an 50 arch dam, many arch dams through incorrect design or construction have developed cracks, which under the influence of temperature changes and the varying water-pressure open and close periodically. This 55 endangers the stability of the structure. I improve the strength of such a dam by casting concrete slabs 11 against the faces 16 of the existing dam 17 and embed in said slabs 11 sufficient metal reinforcement 13 to 60 take care of the tensile stresses occurring in the arch under pressure. To insure a good bond between the existing masonry core 17 and the new concrete slabs 11, I drill holes 18 into said existing core 17 and anchor 65 steel bars 19 into the holes 18, said bars ex-

tending well into the slabs 11, being fastened eventually to the slab reinforcement 13.

I am aware that prior to my invention dams have been built which possess certain features in part similar to the ones described 70 above. I therefore do not claim such combinations broadly; but

I claim—

1. A single-arch dam having preponderantly cantilevering and preponderantly 75 arching parts, the thickness of said dam in horizontal planes being greater near the abutments than near the crown.

2. An arch dam of such a shape that horizontal planes cut both up-stream and down-stream faces of said dam along lines which 80 are substantially circular in form, the centers of these circles being non-coincident, the center of the down-stream circle lying further up-stream than the center of the 85 up-stream circle.

3. An arch dam of varying radii of curvature, said dam being thicker at upper elevations than at lower ones, substantially as 90 described.

4. An arch dam comprising a plurality of superposed arches, the thickness of such arches being larger in upper horizontal planes than in lower ones, such arches in the upper portion of said dam projecting 95 out in varying amounts beyond other arches below.

5. A reinforced arch dam comprising superposed arches, the thickness, reinforcement and strength against axial compression of such arches being larger in upper horizontal planes than in lower one's substantially as described. 100

6. An arch dam comprising a preponderantly cantilevering and a preponderantly 105 arching part, said cantilevering part being subdivided into a plurality of walls substantially parallel to the axis of the dam.

7. A reinforced concrete arch dam comprising superposed arches and a plurality 110 of vertical cantilever slices, the thickness of such arches being larger in upper horizontal planes than in lower ones, said cantilever slices deflecting elastically under their share of the water load at any elevation of 115 the dam substantially as much as said arches at that same elevation, if said arches have to support the full water load and also are shortened by a decrease of temperature at the dam crest of not less than 15° Fahr. below the closing temperature of the dam, substantially as described. 120

8. An arch dam comprising a preponderantly cantilevering and a preponderantly arching part, said arching part comprising 125 superposed arches, the thickness of such arches being larger in upper horizontal planes than in lower ones, the cantilevering part of said dam being anchored to the rock foundation by means of metal bars. 130

9. In an arch dam the combination of an enlarged base of masonry and a plurality of superposed arches, the thickness of such arches being larger in upper horizontal planes than in lower ones, said arches being anchored to said enlarged base by means of metal bars.
10. An arch dam comprising a plurality of superposed arches, the thickness of such arches being larger in upper horizontal planes than in lower ones, said arches having a core of rubble masonry, concrete slabs placed against said core, said concrete slabs being reinforced by metal bars.
11. An arch dam having both faces inclined in a down-stream direction, the said dam being thickest in vertical planes at a point intermediate its top and base and hav-

ing its base portion subdivided into a plurality of vertical parallel planes.

12. An arch dam having both faces inclined in a down-stream direction, the thickness of said dam in any horizontal plane being greatest adjacent the abutments and the thickness of said dam in vertical planes being greatest at a point intermediate its top and base, the entire lower portion of said dam being provided with a vertically extending space between the two faces thereof.

In testimony whereof I have hereunto set my hand in the presence of two subscribing witnesses.
